CLOTHES WRINGER

Walter L. Kauffman, II, Erie, Pa., assignor to
Lovell Manufacturing Company, Erie, Pa., a
corporation of Pennsylvania

Application October 5, 1939, Serial No. 298,094

6 Claims. (CL. 68—254)

In the operation of clothes wringers, the wringer is very frequently reversed with relation to the side from which the clothes are fed. When this is done it is desirable to reverse the means for deflecting the water expressed by the wringer back into the receptacle from which the clothes are fed. The present invention is designed to accomplish this purpose automatically as the direction of rotation of the wringer is reversed. The invention is an improvement on the structure disclosed in my Patent No. 1,955,190.

In the previous structure a rubber tube engages the underside of the lower roll and frictionally engages that roll. This tube is mounted on a tilting drip board and the drip board is reversed through the frictional engagement of the tube with the roll. Where the surfaces of the tube engaged by the roll are made constant there is a tendency for the friction of the roll to heat the tube. This involves an excess of friction and tends to deteriorate the rubber surface of the rubber tube. The present invention is designed to obviate this difficulty. Features and details of the invention will appear from the specification and claims.

A preferred embodiment of the invention is illustrated in the accompanying drawings as follows:

Fig. 1 shows a front elevation of a wringer partly in section embodying the invention.

Fig. 2 a section on the line 2—2 in Fig. 1.

Fig. 3 a similar section with a drip board in a position assumed during reversal.

Fig. 4 a perspective view of a support for the reversing tube.

Fig. 5 shows an elevation of a wringer partly in section illustrating a modification.

Fig. 6 an enlarged section on the line 6—6 in Fig. 5.

Fig. 7 a similar section with the drip board partly reversed.

Fig. 8 a perspective view of the reversing tube support.

Fig. 9 a section on the line 9—9 in Fig. 6.

Fig. 10 a similar section showing a modification of structure.

In the structure illustrated in Figs. 1 to 4, 1 marks a base of the wringer frame, 2 the stiles of the wringer frame. These are of ordinary construction and, as shown, the stiles are of box like form in cross section. Wringer rolls 3 and 4 are provided with shafts 5 and 6 respectively. The shaft 5 of the lower roll is journaled in bearings 7, these bearings resting on bases 8 in the stile. The shafts 6 are journaled in bearings

9 slidably mounted in the stiles. A spring 10 rests on the bearings 9 and is adjustable by screw 11 in a top bar 12. A resetting device 13 is adapted to reset the top bar in position and to be tripped by trip bar 13a. This resetting and tripping mechanism are of well known construction and may be of any desired construction.

A water board 14 is secured by screws 15 on the base 1. This water board has upright flanges 16 at each end and a drip board 17 likewise having flanges 18 is pivotally mounted on the water board by means of pivot pins 19 extending through the flanges.

A rubber tube 20 is mounted in a slot 21 between return ends 22 and a base 23 of a tube support. The tube support has an opening between the ends 22 sufficient to permit the assembly of the tube into the slot 21. The wall of the tube which extends through the slot is slidably mounted in the slot, and the upper portion of the tube engages the periphery of the lower roll.

The frictional engagement during the ordinary running of the wringer is not very great and tends to hold the drip board in the position toward the side from which the clothes are fed. When the wringer is reversed the friction is sufficient to reverse the drip board, the tube yielding to permit its passage under the lower roll.

The frictional engagement of the rubber tube on the lower roll tends to heat the tube and this heating wears the tube and causes a deterioration. In the present invention when the tube gets warm there is enough pull on the tube to effect a rotative movement of the tube through the slot 21, thus providing a fresh surface of the tube to the wringer. Not only this, but this creeping possibility of the tube increases the life of the tube in that it distributes the wear throughout the whole periphery of the tube.

In the modification shown in Figs. 5 to 9, the wringer parts are the same except that the base 1a is of trough shape having a discharge opening 25 surrounded by flange 25a. The drip board 17a has flanges 18a. These flanges extend to each side of the flanged opening 25. A pivot rod 26 extends across the opening through the flange 25a and through the flanges 18a, thus forming a pivotal support for the drip board below the opening.

A support 27, preferably U-shaped, has openings 28 in each arm through which the rod 26 extends forming a pivot for the support. The lower end of the arms have fingers or projections 29 which extend into a groove 30 in the bottom

of the drip board, thus locking the drip board and the support together. Fingers 31 are struck out of the upper portion of the support forming a slot 32 between these fingers and the wall of the support. A space or opening 33 is provided between the ends of the fingers 31 by means of which a tube 20, similar to the tube illustrated in Fig. 1, may be assembled. The tube 20 operates on this support as in the preceding structures, engaging the lower roll of the wringer and effecting the reverse of the drip board below the opening when the roll is reversed.

In Fig. 10 there is a slight modification in that the U-shaped support 34 is provided with a cross pin 35 forming a slot 36 for the reception of the tube. The return ends of the arms of the support 34 extend through openings 37 in the bottom of the drip board, the ends of the arms having projections extending into the openings and locking the support with the drip board.

What I claim as new is:

1. In a wringer having a wringer frame; a roll mounted in the frame; and a water deflecting drip board pivotally mounted below the roll; the combination with the roll and drip board of a reversing device comprising a slotted support connected with the drip board; and a resilient tube having its wall slidably mounted in the slot, said tube engaging the roll.

2. In a wringer having a wringer frame; a roll mounted in the frame; and a water deflecting drip board pivotally mounted below the roll; the combination with the roll and drip board of a reversing device comprising a slotted support connected with the drip board; and a resilient rubber tube having its wall slidably mounted in the slot, said tube engaging the roll.

3. In a wringer having a wringer frame; a roll mounted in the frame; and a water deflecting drip board pivotally mounted below the roll; the combination with the roll and board of a revers-

ing device comprising a slotted support on the drip board; and a resilient rubber tube having its wall slidably mounted in the slot, said tube engaging the roll, one wall of the support being partly open to admit the assembly of the tube.

4. In a wringer having a wringer frame; a roll mounted in the frame; and a water deflecting drip board pivotally mounted below the roll; the combination with the roll and board of a reversing device comprising a slotted support on the board, said slotted support being formed of wire having a base resting on the water deflecting board and return bends extending over the base of the support, the ends of the return bends being separated; and a rubber tube having its wall slidably mounted in the slot, said tube engaging the roll, the opening between the return ends permitting the assembly of the tube in the slot.

5. In a wringer having a wringer frame with a trough at the base, and the trough having a discharge opening through the bottom thereof; a roll mounted in the frame; and a water deflecting board pivotally supported below the opening; the combination with the roll and board and the trough with its opening of a rigid support connected with the board and extending through the opening; and a rubber tube on the support engaging the roll.

6. In a wringer having a wringer frame with a trough at the base, and the trough having a discharge opening through the bottom thereof; and a roll mounted in the frame; the combination with the roll and trough with its opening of a rod extending across the opening; a water deflecting board pivotally mounted on the rod; a support pivotally mounted on the rod and connected with the board and extending through the opening; and a rubber tube mounted on the support and engaging the roll.

WALTER L. KAUFFMAN, II.
